Filed Jan. 19, 1961, Ser. No. 63,621

Term of patent 14 years

(Cl. D26—14)

FIG.1.

FIG.4.

FIG.2.

FIG.5.

FIG.3.

FIG. 1 is a perspective view of a sound transducer, showing our new design;

FIG. 2 is a top plan view;

FIG. 3 is a side elevational view, the opposite side being a mirror image thereof;

FIG. 4 is a front end elevational view; and

FIG. 5 is a rear end elevational view thereof.

The dominant features of the design reside in those portions shown in full lines.

The broken line fragmentary showing of an electrical cord is for illustrative purposes only.

We claim:

The ornamental design for a sound transducer, as shown and described.
